UNITED STATES PATENT OFFICE

ROUVINE POLIAKOFF, OF NEW YORK, N. Y., AND WILLIAM C. ROE, OF DORMONT,
PENNSYLVANIA; SAID ROE ASSIGNOR TO SAID POLIAKOFF

ADVERTISING DEVICE

Application filed July 9, 1927. Serial No. 204,548.

Our invention relates to improvements in machines for exhibiting or displaying cards, plates, panels or placards, having inscribed on their face or faces written, printed or illustrated matter descriptive of some event or circumstance, or for the purpose of advertising.

In the dissemination of news or information and for advertising generally, show cards, posters and like means are at present in extensive use, but due to the fact that if of any considerable size they are generally stationary, and of themselves attract but passing notice, and unless the matter displayed thereon possesses special interest, they soon cease to be attractive to the public and consequently are inadequate to serve as advertising media.

The object of the present invention is to produce a device or machine that will overcome these objections. We accomplish this purpose by means of the device hereinafter more specifically described, reference being had to the accompanying drawings forming part hereof, in which:

Figure 1 is the rear elevation of the machine.

Figure 2 is a fragmentary perspective end view of the roller, showing the slide frame and pawl that lifts the sheets to the roller.

Figure 3 is a fragmentary view of the roller showing the switch arm that transfers the top rod over the back end of the rails.

Figure 4 is a left end view of the roll showing, also, the timing mechanism.

Figure 5 is a fragmentary view showing the right end of roll and driving shaft.

Referring to Figs. 1, 2 and 3 of the drawings, 1, 1, indicate the two side walls of a three-sided frame, in which the operating mechanism is supported. The front of said frame consists of a plate (not shown), the center portion of which, approximately the size of the display sheets, is cut out or removed to produce a view opening, the said opening being closed by a transparent glass sheet, or the entire front may be formed of transparent material. The said walls, 1, 1, are attached to said front at each side of said opening, forming, as heretofore stated, a three-

sided frame which is adapted to be secured in a box, if desired. Near the top on the inside and on opposite sides of said frame, rails or ways 5, 5, are secured or attached, the said rails being slightly inclined towards the front of the frame and the ends 5', 5', thereof adjacent to said front are turned upward to keep the rods 6 on which the display sheets 7 are supported, from being displaced, and terminate at a point a short distance from the front. The said rods are inserted in loops formed along the upper and lower edges of said sheets, and the ends thereof project beyond the edges of said sheets a short distance.

Immediately above said ways 5, 5 a roller 8 is positioned and in the periphery of this roller two short pins 9 and 10 are inserted, the purpose of which will be hereinafter more specifically set forth. The said roller is rigidly mounted upon a shaft 11 journaled in the side walls, whereby when power is applied to said shaft the said roller is caused to revolve. The rotation of said roller subserves two purposes, viz., for shifting or changing the display sheets 7 and for operating the timing mechanism which controls the period of time during which said display sheets are exposed at the view opening. The length of the roller is somewhat greater than the rods 6 and its circumference about one-half the length of the sheets. It is obvious, therefore, that more than one revolution of the roller will be required to shift or change the display sheets; or, in other words, carry the sheets entirely over the roller, and the required rotary movement of the roller to accomplish this purpose is performed by an arrangement of two sets of gears 12, 13, mounted on each end of the roller. The said gears 12, 13, are of a diameter slightly less than the radius of the roller and are pivoted on each end of said roller and are in mesh, the axis thereof being parallel with the axis of the roller. A four toothed star wheel 14 is mounted on said gear 13, and on the outside and near the periphery of the gear 12 is placed a pin 15 on which may be mounted a small roller (not shown) to reduce friction and wear; a flat spring 17 attached to the end of the roller and bearing against one tooth of the star wheel serves to

bring the said wheel into one of its four positions, when rotated, and lock it from turning in a reverse direction; hooked members or pawls 18, rigidly mounted on the shaft 19, which is loosely journaled in the sides of the structure at the top thereof. The said shaft, when actuated by the timing mechanism, as hereinafter set forth, causes said pawls mounted thereon and in vertical alignment 10 with the star wheels on the ends of the roll, to move towards said star wheels and at each revolution of the roll to engage one tooth of the said star wheels $\frac{1}{4}$ of a turn, the said spring tending to retard the wheel from 15 turning a greater distance and to lock it against movement in an opposite direction, whereby the star wheel and the gears make one revolution for every four revolutions of the roller.

20 The reason for using two gears instead of placing the pin in the face of the star wheel is that the gear pin when in contact with other parts would tend to turn the star wheel in the same direction in which it is rotated by 25 the hooked member and the spring would be ineffective as a locking device.

The pin 15, 15 in the gears 12, 12 is so set that when the star wheel is locked in one position the pin will be the nearest to the 30 periphery of the roller that it attains in its rotation, and on a line through the gear center and that of the roller. In this manner any member in line with the pin, when in its extreme position from the center of the roller, 35 will be passed during three revolutions of the roller as the gears will be rotated one-fourth turn at each revolution, and the pin carried towards the center of the roller.

On the inside of the front plate and between the side plates is mounted a slideable frame 20, Fig. 2, which is adapted to slide vertically in grooves. This frame carries two projecting members 21, on the top that contact with the pins 15, 15 in the gears when 45 in their outward position on the roller, also two pawls 22, just below the inside ends of the rails 5, 5 and in line with the ends of the said rods 6, in the display sheets.

The parts mentioned so coordinate that 50 when the roller is rotated, the pins 15, 15 on the gears 12, 12 will contact with the under side of the projection 21 on the top of the slide frame 20 and carry the frame upward. During the upward movement of the frame 55 the upper end of the pawls 22, approach the ends of the rod at the top of the front or first sheet and lift the rod and the upper end of the sheet up to and in contact with the roller 8. The pins in the face of the roller 60 are so placed that when the rod in the upper end of the sheet contacts with the roller the pins will be immediately under the rod and will contact with and carry it over and to the rear of the roller. After the rod is hooked 65 onto the pins 9 and 10 in the roller the pro-

jecting member 21 on the upper end of the slide frame 20 is released from the pin on the gears 12 by the rotation of the roller and said gears and said frame 20 dropping resumes its initial position to carry successively each sheet over and to the rear of the roller. The rod in the end of the sheet is as described carried over by the roller and at the same time the pins 15—15 in the gears 12—12, which is in advance of the leading edge of sheet 7, contacts with the upper surface of arms 23'—23' which forces arms 23—23 toward the face of roller 8 in line with the ends of rod 6 and in advance of said rod. The arms 23—23 are maintained in this position for the period of time necessary for rod 6 to advance and be deflected outwardly from the roller 8 and pins 9 and 10, sliding over the outer surface of arms 23—23. The arms are held in this position by pins 15—15 on gears 12—12 until a substantial portion of sheet 7 is supported upon them, whereupon pins 15—15 slide off cams 15'—15' the ends of the arms 23'—23', thereby releasing the arms and allow them together with arms 23—23 to fall away from the roller surface. The two transfer arms 23 are mounted on short shafts, supported in the side of the frame and act as switches for the rods on which the sheets are mounted. They are so shaped that when in contact with the roller 8 they will lift the first or top rod of the sheets free of the roller and over the back ends of the rails 5, 5, and when in their normal position they guide the second or bottom rod onto said rails. This operation throws the first rod and end of the sheet mounted thereon over and away from the back end of the rails and allows it to drop by gravity to the bottom of the frame. As the arms are restored to normal position before the rod in the opposite end of the sheets reaches this point, the second rod is carried down between the arms 23, 23 and the roller 8 onto the rails 5, 5 and thereby causing the other side of the sheet to be in 100 position for display when engaged by the transfer roller 8.

As it requires more than one revolution of the roller to bring the sheets over, the star wheel functions to carry the pins 15, 15 in the gears away from their effective position during the succeeding three revolutions of the roller. It also requires more than one turn of the roller to carry the sheet over the same, and as the short pins 9 and 10 in the roller are effective for only one-half of its revolution, a second roller 25, is provided to press the sheets against the larger or main roller and hold the same in contact therewith at all time.

This roller 25, is about one-fourth the diameter of the main roller, and is spring pressed against the larger one. The surfaces of the rollers are preferably covered with rubber, although this is not essential. The relation of 130

the diameter of the main roller to that of the length of the sheets is such that the sheets are transferred over in less than four revolutions of the roller and the speed of the roller during the inactive part of its cycle can be slowed down so as to expose the various sheets for a definite and pre-determined period of time. The transfer arms that are actuated by the pins in the gears transfer the top end of the sheet over the ends of the rails and also serve to push the series of sheets along the rails and towards the front of the frame after the front or first sheet has been lifted, as shown in Fig. 3.

As the roller carries the top or upper edge of the sheets over the same, the bottom rod in the sheets passes up the glass panel and between the glass and the end of the rails, the pawls on the slide frame pivoting and swinging back as it passes. When the roller is rotating continuously, the said sheets will be successively exposed to view through the glass panel and then carried over to the rear, it being reversed so as to present the opposite side of said poster or placard to view during the next or succeeding cycle, depending upon the number of placards to be exhibited.

The rotation of said roller also actuates a timing mechanism Figs. 4 and 5 which consists of a train of gears, a set of levers and a cam, hereinafter more specifically described, and to accomplish this purpose the shaft 11, has mounted thereon at one end thereof, a sprocket wheel 26, through which power is transmitted to said roller from any suitable source of power, and through said roller to the timing mechanism actuated thereby. Upon the opposite end of said shaft, a gear wheel 27 is mounted, which meshes with and transmits power to a larger gear wheel 28. In the form of apparatus shown, the said wheels are geared in the ratio of four revolutions of said wheel 27, to one of said wheel 28. The said gear wheel 28 is mounted on a short shaft 29, secured in one of the side walls of the frame, upon which a small gear wheel 30 is mounted, which meshes with and transmits power to the large gear wheel 31, mounted on a short shaft 32, likewise journaled in said side wall. Upon the extreme outer end of said shaft 32, is mounted a small gear wheel 33, which meshes with and transmits power to the large gear wheel 34, mounted on the short shaft 35, upon the extreme outer end of which is mounted the cam 36. The gear mechanism and cam just described in conjunction with the horizontal lever 37, one end of which is pivotally mounted in the frame, and the vertically disposed lever 38, the lower end of which is pivotally mounted in said frame, constitute the timing mechanism which controls the period of time during which the placard or panel is exposed stationary at the view opening. The said cams have project-

ing from their periphery one or more lugs *a*, *b*, which when either thereof contact with the lug *c* on the lower edge of the lever 37, serve to lift the same out of engagement with the pin *d* in the side of the lever 38 and permits the same to swing on its pivotal connection for the purpose of releasing the pawl 18 which permits the hook on the pawl to engage the star wheel for four revolutions of said roller, at the end of which the pin *b'* on gear 28 will engage the inclined inner edge of the lever 38, throwing the same forward into contact with the lower end of the arm X rigidly mounted on the shaft 19, thus rotating said shaft 19 and the pawls 18 which are rigidly secured to said shaft at opposite ends thereof, a sufficient distance to disengage the said pawls from the star wheels thereby throwing the same out of engagement with the star wheel. The lever 37 falling into engagement with the pin on the lever 38, locks it in inoperative position during and following the revolutions of the roller, or until the lever 37 is again operated by the cam. By substituting cams with one or more lugs the period of exposure of the sheets can be changed.

Having described our invention, what we claim and desire to secure by Letters Patent is:

1. In an advertising device, the combination of a frame having a view opening therein, a roller mounted in said frame, a series of display sheets suspended beneath said roller and adjacent to the view opening, guides on which said sheets are successively arranged, means to actuate said roller, means actuated by said roller to successively withdraw said sheets from said view opening, and means adjacent to the rear of said roller to engage and remove each sheet from the roller at predetermined intervals and cause said sheets to pass to the rear of the series of sheets on said guides and in a reverse position.

2. In an advertising device the combination of a frame having a view opening therein, a roller mounted in said frame, a series of display sheets suspended beneath said roller and adjacent to the view opening, guides on which said sheets are successively arranged, means to actuate said roller, means actuated by said roller to successively withdraw said sheets from said view opening, said means including means to elevate said sheets and reverse the face thereof, the said means including a vertically movable frame for conveying said sheets at successive intervals on to said roller and guide arms positioned at the rear of said roller for positioning the sheets successively on the guides after each has passed over the roller.

3. In an advertising device the combination of a frame, the front face of which is formed of transparent material, a roller mounted in said frame, ways secured in the

- 3.5 sides of said frame, a series of sheets, suspended from said ways and beneath said roller, means to support said sheets upon said ways, whereby each sheet is successively presented at the front of said frame, means to regulate the time during which said sheets are exposed at the front of said frame, including timing mechanism operated by the rotation of said rollers, means to elevate the 10 said sheets successively to said roller, including a vertically movable frame, adapted to engage the said sheets and elevate the same to the roller, means to position the said sheets upon the ways, including arms positioned 15 immediately to the rear of said roller.
4. In an advertising device, a series of sheets having display matter on their opposite faces, opposed rails from which said sheets are suspended, a roller journaled above 20 said rails, sheet supporting means on said roller, means for operating said roller, means for successively lifting said sheets at predetermined intervals from said rails onto the supporting means of the roller, whereby each 25 sheet is carried around the latter to an inverted position at the rear of the series, and means for transferring said sheets from the roller onto said rails.
5. In an advertising device, a series of 30 sheets having display matter on their opposite faces, opposed rails from which the sheets are suspended, a roller journaled above said rails, means for operating said roller, sheet supporting means on said roller, means actuated by the roller for successively lifting said sheets from said rails onto the said supporting means of the roller, whereby each sheet is carried around the latter to an inverted 35 position at the rear of said series, and means actuated by said roller for transferring said sheets from the latter onto the said rails.
6. In an advertising device, a series of 40 sheets having display matter on their opposite faces, opposed rails from which the sheets are suspended vertically, a roller journaled above said rails, sheet supporting means carried by the roller, said sheets being singly exposed to view while suspended from said 45 rails, timing mechanism operated by said roller for regulating the time during which each sheet is exposed to view, means for successively lifting said sheets from said rails onto said supporting means of the roller, whereby each sheet is carried around the latter to an inverted 50 position at the rear of the series, and means for transferring said sheets from the roller onto the rails.
7. In an advertising device, a series of 55 sheets having display matter on their opposite faces, opposed rails from which said sheets are suspended vertically, a roller journaled above said rails, sheet supporting means carried by the roller, means for successively lifting said sheets at predetermined intervals 60 from said rails onto said supporting means of

the roller, whereby each sheet is carried around the latter to an inverted position at the rear of the series, and means controlled by said roller for transferring the sheets from the roller onto said rails, and including vertically disposed arms mounted for movement toward and away from said roller at predetermined intervals. 70

8. In an advertising device, a series of sheets having display matter on their opposite faces, opposed rails from which said sheets are suspended vertically, a roller journaled above said rails, sheet supporting means carried by said roller, means for successively lifting said sheets at predetermined 75 intervals from said rails onto the supporting means of the roller, whereby each sheet is carried around the latter to an inverted position at the rear of the series, vertically disposed arms arranged at the rear of the rollers and normally spaced therefrom, said arms being mounted for movement toward and away from said roller, and means for moving said arms against the roller as the sheet approaches said arms, said arms returning to their normal position when released from said means, whereby said arms function to guide one end of the sheet onto the adjacent ends of said rails. 80

9. In an advertising device, a series of 85 sheets having display matter on their opposite faces, opposed rails from which said sheets are suspended vertically, a roller journaled above said rails, sheet supporting means on said roller, a rotatable gear mounted on each end of the roller, a pin carried by said gear, pawl and ratchet mechanism for rotating said gear a predetermined distance during each revolution of said roller to regulate the position of said pin, means including said pin for successively lifting said sheets at predetermined intervals from said rails onto said supporting means of the roller, whereby each sheet is carried around the roller to an inverted 90 position at the rear of said series, and means for transferring said sheets from the roller onto said rails. 100

10. In an advertising device, a series of 105 sheets having display matter on their opposite faces, opposed rails from which the sheets are suspended vertically with the outermost sheet in display position, a roller journaled above said rails, sheet supporting means on said roller, gears journaled on the ends of the roller, a pin carried by one of each set of gears, pawl and ratchet mechanism for rotating said gears a predetermined distance during each revolution of the roller to control 110 the position of said pins, means including said pins for successively lifting said sheets from said rails onto the supporting means of the roller, whereby each sheet is carried around the latter to an inverted position at the rear of the series, and means actuated 115

by said pins for transferring each sheet from the roller onto said rails in an inverted position.

11. In an advertising device, a series of sheets having display matter on the opposite faces, opposed rails from which said sheets are suspended vertically with the outermost sheet in display position, a roller journaled above said rails, timing mechanism operated by said roller to regulate the time during which each sheet is exposed, sheet supporting means on said roller, a gear journaled on each end of the roller, a pin carried by each gear, means including a pawl and ratchet for rotating said gears a predetermined distance during each revolution of the roller to control the position of said pins, a vertically movable frame intermittently lifted by said pins to remove said sheets singly from the rails onto the supporting means of the roller, whereby each sheet is carried around said roller to an inverted position at the rear of the series, and means for transferring said sheets from the roller onto said rails.

In testimony whereof, we have hereunto signed our names.

ROUVINE POLIAKOFF.
